UNITED STATES PATENT OFFICE

98,663

DESIGN FOR A DISPLAY LIGHT FOR AN AUTOMOBILE

Doyle Duff, Burton, and John C. Elliott and Jacob J. Flickinger, Halstead, Kans.

Application November 5, 1935, Serial No. 59,397

Term of patent 14 years

To all whom it may concern:

Be it known that we, Doyle Duff, John C. Elliott, and Jacob J. Flickinger, citizens of the United States, residing at Burton, Halstead, and Halstead, respectively, in the county of Harvey and State of Kansas, have invented a new, original, and ornamental Design for a Display Light for an Automobile, of which the following is a specification, reference being had to the accompanying drawing, forming part thereof.

Figure 1 is a view in front elevation of a display light for an automobile showing our new design; and

Figure 2 is a view in side elevation.

We claim:—

The ornamental design for a display light for an automobile, as shown.

DOYLE DUFF.
JOHN C. ELLIOTT.
JACOB J. FLICKINGER.
